UNITED STATES PATENT OFFICE.

FRANK. S. MITCHELL, OF POCATELLO, IDAHO TERRITORY.

RAILROAD-SWITCH-STAND LOCK.

SPECIFICATION forming part of Letters Patent No. 379,122, dated March 6, 1888.

Application filed September 16, 1887. Serial No. 249,829. (No model.)

To all whom it may concern:

Be it known that I, FRANK. S. MITCHELL, a citizen of the United States, residing at Pocatello, in the county of Bingham and Territory of Idaho, have invented certain new and useful Improvements in Railroad-Switch Locks; and I do hereby declare that the following is a full, clear, and exact description of the same, reference being had to the annexed drawings, making a part of this specification, and to the letters and figures of reference marked thereon.

Figure 1 of the drawings is an elevation of my invention, showing the signal and signal-pole, also the signal-stand and the operating-lever in an elevated position in dotted lines. Fig. 2 is a detail view, partly in section, and on an enlarged scale, of the locking mechanism; Fig. 3, a top plan view thereof, partly in section; Fig. 4, a detail view in perspective of the bolt, and Fig. 5 a detail view of the key.

The present invention has for its object to provide a simple and effective means for locking in position a railroad-switch, and also in releasing it when required; and it consists in the details of construction, substantially as shown in the drawings, and hereinafter described and claimed.

In the accompanying drawings, A represents the circular switch-stand, having connected thereto the plate B, and through this stand extends the signal-pole C, provided with the usual signal, D, all of which are of the ordinary construction.

To the pole C is suitably connected a bracket, E, of any preferred construction, to which the operating parts of the locking mechanism are connected, which consist as follows: Extending transversely through the bracket E is a short shaft, a, provided at or near its center with a cam, F, said cam fitting or engaging with the socket b of a bolt, G, whereby said bolt is operated when the shaft is turned. This shaft is connected in any suitable manner to a hand-lever, H, for operating it, and when the lever is pressed down, as shown in full lines, Fig. 1, the cam F will move the bolt over the switch-plate B, and when the key is turned, as will be hereinafter described, the

switch will be locked in position. One end of the shaft a is slotted, as shown at c, to receive a tumbler, I, retained therein by a spring, d, the key-opening being covered by an escutcheon, e, and key-hole guard f.

The key J, which is represented in Fig. 5, is preferably formed of flat steel, and when inserted in the slot in the end of the shaft a it is enabled to turn it and draw the bolt back, thereby unlocking the switch and allowing the lever H to be raised, as shown in dotted lines. The key cannot be removed until the switch is locked again; but when removed the tumbler I will be forced by the spring d into the slot c of the shaft. The shaft a at its slotted end is somewhat larger in diameter and formed with a groove around its periphery, as shown at g, in which rests a transverse pin, h, on the tumbler I, so as to keep it in position.

The bracket E has a recess, i, to allow a pin, K, to work back from engagement with a socket, k, in the bolt G, thereby enabling the bolt to be brought to a locking position. The meeting faces of the pin and socket are inclined, as shown, so that when the bolt is moved to a locking position the inclines, coming in contact with each other, will force the pin out laterally in the recess i, and when the bolt is moved back the pin will engage with the socket k. After the switch has been unlocked, by raising the lever H the pin K is caused to slide in position to engage with the socket in the bolt, which locks both the bolt and key in position, thus preventing the key being removed until the lever H is pressed down and the switch is locked.

The plate B, as will be noticed, has recesses m extending inward from its periphery, in which the lever engages when it is pressed down, and in the rear of these recesses are pins l, the object of which is to prevent the bolt G from sliding far enough to allow the key to be removed.

A very simple, effective, and secure means is provided for locking or unlocking the switch, and, it being positive in its action, there is no danger of accidents by its failure to work.

Having now fully described my invention, what I claim as new, and desire to secure by Letters Patent, is—

In a lock for railroad switches, a handle-
5 lever, a socketed sliding bolt, and a pin for en-
gaging therewith, in combination with a cam-
shaft for operating the bolt, having a slot at
one end, and a dog for engaging with the slot,
substantially as and for the purpose set forth.

In testimony that I claim the above I have to
hereunto subscribed my name in the presence
of two witnesses.

FRANK S. MITCHELL.
